VENTILATED BACK REST

Lura B. Farrell, Coshocton, Ohio

Application August 17, 1938, Serial No. 225,311

3 Claims. (Cl. 155—182)

The principal object of the instant invention is the provision of an attachment for seats in the nature of upholstered chairs, davenport, car seats and the like, which attachment is specially constructed to provide a ventilated space between the back of the user and the upholstered portion of the seat against which the user would normally rest.

During the months of the year when temperatures rise to a point where the user of upholstered furniture or car seats experiences discomfort in view of the lack of ventilation between portions of the body and parts of the said seats, attachments of the character embodying this invention become extremely desirable.

One of the primary aims of the invention, therefore, is the provision of a seat attachment that may be conveniently and quickly moved to position between the back of the user and the back of the particular upholstered seat so as to provide ample space for the circulation of air.

Another important aim of this invention is to provide an attachment of the aforementioned character, that may be quickly collapsed to an inoperative position and stored in a flattened condition, portions of the structure of the attachment being particularly made so as to hold the parts thereof in the normal operative position after the same has been conditioned for use.

Another important object of this invention is to provide a seat attachment that is exceptionally simple to manufacture, includes a minimum number of parts, and has as a portion thereof a base upon which advertising may be spread so that the attachment may be employed as an advertising medium or premium by manufacturers and distributors.

The invention contemplates a large number of minor objects, each of which is important to the successful operation of the attachment, and the said minor objects including details of construction, will be made clear during the course of the following specification, referring to the accompanying drawing wherein:

Figure 1 is a perspective view of a seat attachment embodying this invention.

Fig. 2 is a top edge view of the same.

Fig. 3 is a side elevation of the seat attachment.

Fig. 4 is an enlarged fragmentary detailed sectional view taken on line IV—IV of Fig. 3; and,

Fig. 5 is a fragmentary view illustrating the lower portion of a seat attachment made to embody a modified form of the invention.

The seat with which this attachment is particularly useful is of the upholstered type, either

in the nature of an automobile seat, davenport or other similar piece of furniture. In the illustrated instance, this seat comprises a back 8 and a bottom 10. The attachment per se rests upon the seat as illustrated in Figs. 1 and 3, and comprises a base 12 which may be made of any suitable seat material, such as metal, plywood, composition board and the like.

This base 12 should be strong enough however, to withstand the pressure exerted thereon and also to carry resilient rods 14, one of which is positioned along each of two opposite edges of base 12. These rods 14 have the portions in the ends thereof inturned to pass through base 12 and it is at this part of the rods that the same are secured to base 12. Each rod 14 has hingedly mounted thereon a bracket 16 that is substantially U-shaped and provided with eyes 18 at each end thereof. These eyes are looped around the respective rods 14 so that brackets 16 may be swung to and from the normal position shown in the drawing.

When the attachment is to be collapsed and stored, brackets 16 are hinged down against the face of base 12 to lie thereagainst.

It has been found desirable to provide links 20 intermediate the ends of brackets 16. These links are rigidly secured at their one end to brackets 16 and their other ends thereof are provided with eyes 22 which encircle rods 14. Thus, the U-shaped brackets 16 are securely but hingedly carried by rods 14.

A plurality of flexible strips 24 extend between the two brackets 16 and are in spaced relation to base 12 when the attachment is expanded for use. Each of these strips 24 is constructed of flexible fabric material and is provided with an opening 26 near each bracket 16.

A suitable buckle 28 at the ends of each strip 24 secures the strip in position so that it is in frictional engagement with one side of base 12. When the attachment is assembled, the strips 24 are attached to the brackets by a loop 30 that is formed in the strip by passing a portion thereof through each of the holes 26 and around the bight of U-shaped rods 16. When the brackets are in a plane extending perpendicular to the plane of base 12, the length of strips 24 between brackets 16 engages the back of the user and presents a comfortable, yieldable support that affords ample ventilation.

To collapse the attachment, buckles 28 of strips 24 may be loosened whereupon brackets 16 will move inwardly against the face of base 12.

A bumper 32 should be secured along one edge

of base 12 to protect the surface of seat 10. In the preferred embodiment of the invention, this bumper is a channel made of soft rubber or similar resilient material that has a rounded outer 5 surface which reduces the wear on seat 10 to a minimum.

In the form of the invention illustrated in Fig. 5, this bumper 32 is in the nature of a flap 34 that extends around the edge of base 12 and outwardly therefrom. Flap 34 may be of fabric or some suitable material such as matting that would be cooler than the normal fabric forming the upholstery of seat 10.

It is obvious from the foregoing that an attachment embodying this invention may be used with any upholstered seat to an advantage. The size of the attachment may be altered to suit conditions and the number of strips 24 as well as their width may be determined by the use to which the attachment is to be put. It will also be clear to one skilled in the art that seat attachments having physical characteristics other than that shown in the drawing might be made without departing from the spirit of the invention or scope of the appended claims.

Having thus described the invention, what is claimed as new and desired to be secured by Letters Patent is:

1. A seat attachment of the character described comprising a rigid base; a bracket hingedly mounted on the base along each of two opposite edges of the base and extending laterally from one side thereof; and a plurality of flexible strips joining the brackets at their outermost portions and held in spaced relation to the base thereby, said strips each being looped around each bracket and extended around the other side of the base and in engagement therewith,

the ends of said strips being connected together for the purpose specified, said base having an apron along one edge thereof for engaging the horizontal surface of the seat.

2. A seat attachment of the character described comprising a rigid base; a bracket hingedly mounted on the base along each of two opposite edges of the base and extending laterally from one side thereof; and a plurality of flexible strips joining the brackets at their outermost portions and held in spaced relation to the base thereby, each of said strips being provided with an opening therethrough adjacent to each bracket, the portions of the strips at the brackets being looped around the brackets and passed through said openings, said strips being extended around the other side of the base and in engagement therewith, the ends of said strips being connected together.

3. A seat attachment of the character described comprising a rigid base; a resilient rod on one side of the base along each of two opposite edges respectively thereof, said rod having a major portion of its length spaced from the face of said base; a substantially U-shaped bracket having eyes formed on the ends thereof to receive the said rod, carried by each rod respectively; a plurality of flexible strips joining the bights of said U-shaped brackets and extending across and engaging the other side of said base, said strips having their ends connected together; and means at the ends of said strips for detachably holding the same together, each strip being looped around one of the said bights of the U-shaped brackets to preclude accidental swinging thereof about the rods supporting the brackets.
